UNITED STATES PATENT OFFICE.

**ALBERT F. SAUNDERS, OF SYRACUSE, NEW YORK, ASSIGNOR TO T. N. BENEDICT MFG.
CO., OF EAST SYRACUSE, NEW YORK, A CORPORATION OF NEW YORK.**

DESIGN FOR A CUP.

52,350.

Specification for Design.

Patented Aug. 27, 1918.

Application filed April 15, 1918. Serial No. 228,780. Term of patent 7 years.

To all whom it may concern:

Be it known that I, ALBERT F. SAUNDERS, a citizen of the United States, residing at Syracuse, in the county of Onondaga and State of New York, have invented a new, original, and ornamental Design for a Cup, of which the following is a specification, reference being had to the accompanying drawing, forming a part hereof.

Figure 1 is a plan view of a cup embodying my design.

Fig. 2 is an elevation thereof.

This design comprehends a body in the general form of an inverted truncated cone having an annular bulge just above the base line, the surfaces of which merge in easy curves in the surfaces of the contiguous

parts of the body, and a handle jointed at its upper end to the body above the central portion thereof and at its lower end to the annular bulge, the handle being in the general form of the outline of one-half of a heart, the handle tapering from its upper portion toward its lower end and having enlargements where it joins the body and the bulge.

I claim:

The ornamental design for a cup substantially as shown and described.

In testimony whereof I have hereunto signed my name, at Syracuse, in the county of Onondaga and State of New York, this 5th day of April, 1918.

ALBERT F. SAUNDERS.
